FIG. 2

UNITED STATES PATENT OFFICE

2,133,341

CIGARETTE TIPPER

Wilhelm B. Bronander, Montclair, N. J., assignor
to American Machine & Foundry Company, a
corporation of New Jersey

Application February 26, 1935, Serial No. 8,363

29 Claims. (Cl. 131—39)

This invention relates to an improved tipping mechanism to be used in conjunction with continuous-rod cigarette machines, wrapping machines, or label-applying machines, its main object being to produce a device suitable for operation at high speed and operating to continuously feed the tipping material.

To this end the web of cork or other suitable tipping material is continuously fed from a reel by two coacting feed rollers and is cut at predetermined intervals by cutters supported in a revolving drum. The cut portions, which are each of a length sufficient to provide cork tips for two cigarettes, are transported by the cutting edge of the cutters to a position where their leading ends are nipped between the rotating drum and a rotating segmental roller around which passes the web of wrapping material which is to be tipped. The severed portions are thereby fed lengthwise onto the web of wrapping material.

Paste is applied to the wrapping material at equal intervals by means of a rotating paste applicator; this member engaging a paste wheel before contacting with the web. The web of wrapping material so prepared is carried around the segmental roller heretofore mentioned, in such a manner that the severed portions of tipping material advanced by the cutters are brought into register and pressed into adhering relation with the paste spots on the wrapping material. The tipped web is then led to feed rolls which advance it toward the cigarette machine.

A further object of the invention is to stop the feeding of the webs of tipping and wrapping material when either web is broken or exhausted and to prevent the application of paste to the wrapping material when the web of tipping material is broken or exhausted. In pursuance thereof the tipper is provided with automatic mechanism for moving the web of wrapping material out of operative relation to the paste applicator when the web of tipping material is broken or exhausted, thus permitting the wrapping material to pass freely by the applicator without being pasted and thereby preventing smearing of paste on the cutter drum or the cigarette making machine when the tipping material fails to feed. The described device also disengages a clutch on the main shaft of the cigarette machine, thus stopping the machine and thereby preventing the making of untipped cigarettes therein. This mechanism consists of a cam-operated arm carrying a contact finger connected

with the winding of an electromagnet and so timed as to periodically engage the tipping material as it is fed between the cutter drum and the ledger plate. When no tipping material has been fed, this finger makes contact with the cutter drum, thereby completing an electromagnetic circuit which controls the mechanism for moving the wrapping material away from the paste applicator and also controls the clutch operating means.

The tipper is also provided with a contact finger which rests against the traveling web of wrapping material while the same is continuously fed. When the web of wrapping material breaks or is exhausted, the finger makes contact with a roller through which its connections energize the electromagnetic circuit which controls the clutch operating means. In this manner the feeding of the tobacco is stopped in the cigarette machines and wasting of tobacco avoided.

In the accompanying drawing which forms a part of this specification and in which like characters of reference indicate the same or like parts:

Fig. 1 is a plan view of the improved tipper; and

Fig. 2 is a side elevation of the same.

In carrying the invention into effect there is provided mechanism for continuously advancing a web of wrapping material, mechanism for continuously advancing a web of tipping material, a device for applying paste at predetermined intervals to the web of wrapping material, a cutter operating to sever portions from the traveling web of tipping material and by itself advance them into register with the pasted sections of the web of wrapping material, and means for pressing the registered portions into adhering relation with the web of wrapping material. In the best constructions there is provided means for incapacitating the mechanisms for feeding the webs of tipping and wrapping material whenever either web is broken or exhausted, and there is also provided means for moving the web of wrapping material out of operative relation to said paste-applying device whenever the web of tipping material is broken or exhausted.

These various means and parts may be widely varied in construction within the scope of the claims for the particular device selected to illustrate the invention is but one of many possible concrete embodiments of the same. The invention, therefore, is not to be restricted to the specific construction shown and described.

Referring to the drawing, a drive shaft 10 is

equipped with a female clutch member 11 loosely mounted thereon and engaging a male clutch member 12 fastened on the main shaft 13 of the cigarette machine, wrapping machine, or other type of machine to which the tipper is attached. To the shaft 13 is attached a helical gear 14 meshing with a helical gear 15 mounted on the jack-shaft 16, the shaft 16 also carrying a sprocket (not shown) which drives a chain 17 over a sprocket (not shown) mounted on the drum-shaft 18.

Shaft 18 carries a pinion 19 meshing with a gear 20 mounted on shaft 21, the gear 20 meshing with a gear 22 which drives a gear 23. Gears 22 and 23 are mounted on shafts 24 and 25 respectively, and shafts 24 and 25 carry the feed rollers 26 and 27, respectively, which coact to feed the web of tipping material C.

The shaft 18 also carries a gear 28 meshing with an intermediate gear 29 on shaft 30, gear 29 meshing with a gear 31 mounted on shaft 32. On shaft 32 is also mounted a gear 31a which drives a gear 33 mounted on shaft 34, and the gear 33 drives a gear 35 mounted on shaft 36. A pinion 37 on a shaft 38, which also carries a pinion 37a, is driven by the gear 35; and the pinion 37a drives a gear 39 mounted on a shaft 40 supported in bearings of the paste pot 41.

The paste pot 41 is provided with a scraper or doctor 42 which is slidably mounted on the paste pot and equipped with an adjusting screw 43 for adjustment of the scraper 42 closer or farther away from the paste wheel 44 and thereby controlling the amount of paste on the latter. As the wheel 44 rotates it transfers the paste adhering to its periphery to a distributing roller 45 which in turn delivers the paste to a rotating segmental paste applicator 46 clamped on shaft 36.

The web of cork or other tipping material 40 unwound from a reel R by the feed rollers 26 and 27, which advance the tipping material at a speed substantially less than that of the cigarette paper, P, passes through a stationary guide 47, and its leading end enters the clearance space 45 between the concave 48 and the revolving metallic drum 49. This clearance is slightly greater than the thickness of the tipping material. After a length of the web C sufficient for two cork tips has entered said space, the web is nipped against the concave by the cutting edge of either of the diametrically opposite cutters 50 and 50a set in diametral protuberances on the rim of drum 49, and thus severed. The movement of the protuberances relative to the guide 47 tends to 55 smooth the web of tipping material immediately prior to the severance of the strips as well as guide the web under the cutters. For this purpose the cutting edges of the cutters 50 and 50a may extend radially of the drum 48 and project sufficiently from the periphery thereof to nip the proper length of tip material at the entrance to this space and sever it across a ledger plate integrally formed with the concave 48, and slightly raised thereon adjacent said entrance. The 60 cut strips are then pushed along in said space by the cutting edges of the cutters which travel at a linear speed equal to that of the cigarette paper, until their leading ends are nipped between the respective protuberance and the raised 65 segment of a roller, as will be presently described.

While the ledger plate has been described as integrally formed with the concave, it should be understood that hardened steel inserts may be used instead.

75 The web of wrapping material P is drawn from

a reel (not shown) over a metallic roller 51 and around a stud 52 carried by the frame 53. On the stud 52 is pivotally mounted a spring-tensioned arm 53a which during normal operation is held in vertical position by a latch 54. The arm 53a carries studs 55 and 56, and the wrapper web P passes over said studs and between the drum 49 and a roller 57 as it is drawn upwardly by continuously rotating rubber feed rollers (see Fig. 2) driven from the shaft 18 by a gear train 10 (not shown).

The revolving paste applicator 46, which rotates at a greater linear velocity than the speed of the traveling wrapper web P rubs over the section of the latter spanning the studs 55 and 56 and thereby applies paste to the continuously moving wrapper web at the proper intervals. The pasted wrapper web P is then carried around the roller 57; and the cut portion of tipping material which is being advanced by the cutting edge of either cutter 50 or 50a into register with the web P, is pressed thereon as it is nipped between the respective protuberance of the drum 48 and the raised segment of roller 57.

A cam 58 mounted on shaft 18 is provided with 25 diametrically opposite steps 59 which each successively engage the spring-pressed arm 60 and permit the same and a metallic contact finger 61 fastened to its hub to momentarily move inward. In case the reel of tipping material is exhausted 30 or broken, the contact finger 61 during its repeated inward movement eventually makes unobstructed contact through a slot in the concave 48 with a narrow groove in either protuberance of the drum 49, thus completing a circuit through 35 and energizing a solenoid 63 which thereupon pulls down the latch 54 pivotally mounted on a stud 64 and thereby frees the arm 53a. Whenever the arm 53a is thus freed it swings away from the path of the revolving paste carrier 46 with 40 the wrapper web and in so doing, prevents the further application of paste to the wrapper web. At the same time, the electromagnet 65, which 45 is connected in parallel with the solenoid 63, is also energized and attracts an arm 66 connected to the female clutch member 11, thus moving the arm 66 as indicated by the dotted arrow to disengage the clutch members 11—12 and stop the cigarette machine, or other type of 50 machine to which the tipper is attached.

For this purpose, one of the lines 67, which are 55 supplied with current from a suitable source of electric current, not shown, is connected by a lead 68 to a stationary contact 69. When the arm 66 engages one of the steps 59 of the cam 58 and the inner end of the contact maker 61 enters either of the grooves in the protuberances of the drum 49, the outer end of the contact maker is 60 pressed against the contact 69 so that the current flows through a wire 70 to the solenoid 63. The latter is thus energized and trips the latch 54 heretofore described; and the current flowing through the wire 71 to the electromagnet 65 energizes it, thereby actuating the arm 66 to disengage the clutch members 11 and 12, and returns 65 to the other line through the lead 72.

In case the wrapper web P is exhausted or 70 broken, the electromagnet 65 is energized through a branch circuit comprising a lead 73 connected to the line 67 and the roller 51 and a contact 75 finger 74 which is then free to make contact with the periphery of the roller 51. The current then passes through the finger 74 and flows to the electromagnet through a wire 75, returning to the other line 67 through the lead 72. When 75

the electromagnet is energized the clutch arm 66 is actuated to uncouple the clutch member 11 from the clutch member 12, thereby stopping the machine. During normal operation of the machine the contact finger 14 rests on the traveling wrapper web, which acts as an insulator, thus keeping the branch circuit open.

What is claimed is:

1. In a tipper, the combination with mechanism for continuously advancing a web of wrapping material, of mechanism for continuously advancing a web of tipping material, a device for applying paste at predetermined intervals to the traveling web of wrapping material, a rotary cutter operating to sever portions from the traveling web of tipping material and of itself advance them into register with the pasted sections of the web of wrapping material, said cutter being the only means for advancing said portions, and means for pressing the registered portions into adhering relation with the pasted sections of the web of wrapping material.
2. In a tipper, the combination with mechanism for continuously advancing a web of wrapping material, of mechanism for continuously advancing a web of tipping material, a device for applying paste at predetermined intervals to the traveling web of wrapping material, a cutter operating to sever portions from the traveling web of tipping material and of itself advance them into register with the pasted sections of the web of wrapping material, and means for pressing the registered portions into adhering relation with the pasted sections of the web of wrapping material, a concave provided with an integral, slightly raised, ledger plate, a rotary drum mounted within said concave, the clearance between said drum and said concave being slightly greater than the thickness of the tipping material and said cutter being set in the rim of said drum and its cutting edge projecting from the periphery of said drum sufficiently to sever the web of tipping material across said ledger plate and push the severed portions along the concave.
3. In a tipper, the combination with mechanism for continuously advancing a web of wrapping material, of mechanism for continuously advancing a web of tipping material, a device for applying paste at predetermined intervals to the traveling web of wrapping material, a cutter operating to sever portions from the traveling web of tipping material and of itself advance them into register with the pasted sections of the web of wrapping material, and means for pressing the registered portions into adhering relation with the pasted sections of the web of wrapping material, a concave provided with an integral, slightly raised, ledger plate, a rotary drum mounted within said concave, the clearance between said drum and said concave being slightly greater than the thickness of the tipping material and said cutter being set in the rim of said drum and its cutting edge projecting from the periphery of said drum sufficiently to sever the web of tipping material across said ledger plate and push the severed portions along the concave, and said strip-pressing means including a protuberance on said drum, the cutter being set in said protuberance, and a roller having a raised segment disposed to coact with the protuberance to press a pasted section of the web of wrapping material against the severed portion advanced by said cutter.
4. In a tipper, the combination with mechanism for continuously advancing a web of wrapping material, of mechanism for continuously ad-
- vancing a web of tipping material, a device for applying paste at predetermined intervals to the traveling web of wrapping material, a cutter operating to sever portions from the traveling web of tipping material and of itself advance them into register with the pasted sections of the web of wrapping material, and means for pressing the registered portions into adhering relation with the pasted sections of the web of wrapping material, and means for incapacitating the mechanisms for feeding the webs of wrapping and tipping material whenever either web is broken or exhausted, said cutter being the only means for advancing said portions.
5. In a tipper, the combination with mechanism for continuously advancing a web of wrapping material, of mechanism for continuously advancing a web of tipping material, a device for applying paste at predetermined intervals to the traveling web of wrapping material, a cutter operating to sever portions from the traveling web of tipping material and of itself advance them into register with the pasted sections of the web of wrapping material, and means for pressing the registered portions into adhering relation with the pasted sections of the web of wrapping material, and means for incapacitating the mechanisms for feeding the webs of wrapping and tipping material whenever either web is broken or exhausted, a concave provided with an integral, slightly raised, ledger plate, a rotary drum mounted within said concave, the clearance between said drum and said concave being slightly greater than the thickness of the tipping material, and said cutter being set in the rim of said drum and its cutting edge projecting from the periphery of said drum sufficiently to sever the web of tipping material across said ledger plate and push the severed portion along said concave, and said incapacitating means including a driving shaft, a driven shaft connected to and driving said drum, an electro-magnetically controlled clutch connecting said driving and driven shafts, a main electro-magnetic circuit adapted to disengage said clutch, a cam-operated contact maker acting to periodically engage the periphery of said drum within said concave and to close said main electro-magnetic circuit when there are not cut portions of tipping material between said drum and concave, an electrically conductive roller over which the web of wrapping material is drawn, a branch electromagnetic circuit connected to said roller and adapted to disengage said clutch, and a contact maker connected to said branch circuit and bearing on the web of wrapping material traveling over said roller in order to close said branch circuit when the wrapping material is broken or exhausted.
6. In a tipper, the combination with mechanism for continuously advancing a web of wrapping material, of mechanism for continuously advancing a web of tipping material, a device for applying paste at predetermined intervals to the traveling web of wrapping material, a cutter operating to sever portions from the traveling web of tipping material and of itself advance them into register with the pasted sections of the web of wrapping material, means for pressing the registered portions into adhering relation with the pasted sections of the web of wrapping material, and means for moving the web of wrapping material out of contact with said device whenever the web of tipping material is broken or exhausted.
7. The combination with mechanism for con-

tinuously advancing a web of wrapping material, of mechanism for continuously advancing a web of tipping material, a device for applying paste at predetermined intervals to the traveling web 5 of wrapping material, cutting mechanism operating to sever portions from the traveling web of tipping material, means for pressing the cut portions into adhering relation with the pasted sections of the web of wrapping material, and 10 means for moving the web of wrapping material out of contact with said device whenever the web of tipping material is broken or exhausted.

8. The combination with mechanism for continuously advancing a web of tipping material, 15 of cutting mechanism operating to sever portions from the traveling web of tipping material and advance them into predetermined position, and means for incapacitating said mechanism whenever said web is exhausted or broken, said 20 mechanism including a concave with an integral, slightly raised, ledger plate, a rotary drum mounted within said concave and provided with diametrically opposite cutters set in its rim, the clearance between the periphery of said drum 25 and said concave being slightly greater than the thickness of said web, and the cutting edges of said knives projecting from the periphery of said drum sufficiently to sever the web across said ledger plate and push the severed portions along 30 said concave.

9. The combination with mechanism for continuously advancing a web of tipping material, of cutting mechanism operating to sever portions from the traveling web of tipping material and 35 advance them into predetermined position, and means for incapacitating said mechanism whenever said web is exhausted or broken, said mechanism including a concave with an integral, slightly raised, ledger plate, a rotary drum mounted 40 within said concave and provided with diametrically opposite cutters set in its rim, the clearance between the periphery of said drum and said concave being slightly greater than the thickness of said web, and the cutting edges of said knives 45 projecting from the periphery of said drum sufficiently to sever the web across said ledger plate and push the severed portions along said concave, and said means including a driving shaft, a driven shaft connected to and driving said drum, an electromagnetically controlled clutch connecting 50 said driving and driven shafts, an electromagnetic circuit adapted to disengage said clutch, a cam-operated contact maker acting to periodically engage the periphery of said drum within 55 said concave and to close said circuit when there are not cut portions between the drum and concave.

10. The combination with mechanism for continuously advancing a web of wrapping material, 60 of an applicator for applying paste at predetermined intervals to the traveling wrapper web, mechanism for feeding a web of tipping material and severing strips therefrom and applying them to the pasted sections of the wrapping material 65 and means for moving the web of wrapping material out of contact with said applicator whenever said web of tipping material is broken.

11. In a tipper, the combination with mechanism for continuously advancing a web of wrapping material, of mechanism for continuously advancing a web of tipping material, a device for applying paste at predetermined intervals to the traveling web of wrapping material, members 70 arranged and spaced to receive the web of tipping material therebetween and guide the same, a

cutter operating to sever portions from the traveling web of tipping material as it is advanced between said members and of itself advance said severed portions between said members into register with the pasted sections of the web of wrapping material, said cutter being the only means for advancing said portions, and means for pressing the registered portions into adhering relation with the pasted sections of the web of wrapping material.

12. In a tipper, the combination with mechanism for continuously advancing a web of wrapping material, of mechanism for continuously advancing a web of tipping material, members arranged and spaced to receive the web of tipping 15 material therebetween and guide the same, a cutter operating to sever portions from the traveling web of tipping material as it is advanced between said members and of itself advance said severed portions between said members into engagement with the web of wrapping material, said cutter being the only means for advancing said portions, and means for pressing said severed portions into adhering relation with the web of wrapping material.

13. In a tipper, the combination with mechanism for continuously advancing a web of wrapping material, of mechanism for continuously advancing a web of tipping material, members arranged and spaced to receive the web of tipping 30 material therebetween and guide the same, a cutter operating to sever portions from the traveling web of tipping material as it is advanced between said members and of itself advance said severed portions between said members into engagement with the web of wrapping material, and means for pressing said severed portions into 35 adhering relation with the web of wrapping material, said members including a stationary concave and a rotary drum in the rim of which said 40 cutter is set.

14. In a tipper, the combination with mechanism for continuously advancing a web of tipping material, of members arranged and spaced to receive the web of tipping material therebetween 45 and guide the same, and a cutter operating to sever portions from the traveling web of tipping material as it is advanced between said members and of itself advance said severed portions between said members, said cutter being the only 50 means for advancing said portions.

15. In a tipper, the combination with mechanism for continuously advancing a web of wrapping material, of mechanism for continuously advancing a web of tipping material, a device for applying paste at predetermined intervals to the web of wrapping material, a cutter operating to sever portions from the traveling web of tipping material, an immovable member and a moving member arranged and spaced to receive the web 60 of tipping material therebetween and guide the same under the cutter and guide the portions severed therefrom into register with the pasted sections of the web of wrapping material, and means for pressing the registered portions into 65 adhering relation with the pasted sections of the web of wrapping material.

16. In a tipper, the combination with mechanism for continuously advancing a web of wrapping material, of mechanism for continuously advancing a web of tipping material, a cutter operating to sever portions from the traveling web of tipping material, relatively moving members arranged and spaced to receive the web of tipping 70 material therebetween and smooth and guide 75

the same under the cutter and guide the portions severed therefrom into engagement with the web of wrapping material, and means for pressing said severed portions into adhering relation with the web of wrapping material.

17. In a tipper, the combination with mechanism for continuously advancing a web of wrapping material, of mechanism for continuously advancing a web of tipping material, a cutter operating to sever portions from the traveling web of tipping material and advance them on to the wrapping material, and an immovable member arranged to guide the same under the cutter and guide the severed portions into engagement with the web of wrapping material.

18. In a tipper, the combination with mechanism for continuously advancing a web of wrapping material, of mechanism for continuously advancing a web of tipping material, a cutter operating to sever portions from the traveling web of tipping material, and members arranged and spaced to receive the web of tipping material therebetween and guide the same under the cutter and guide the severed portions into engagement with the web of wrapping material, said members including a stationary concave and a rotary drum in the rim of which said cutter is set.

19. The combination with mechanism for continuously advancing a web of wrapping material, of mechanism for continuously advancing a web of tipping material, a device for applying paste at predetermined intervals to the traveling web of wrapping material, mechanism for severing portions from the traveling web of tipping material and pressing them into adhering relation with the pasted sections of the web of wrapping material, and means for moving the web of wrapping material out of contact with said device whenever the web of tipping material is broken or exhausted, said means including a pivoted frame having a plurality of spaced members over which the web of wrapping material passes, and a latch for maintaining said frame in position to cause the portion of the web of wrapping material passing over said members to contact with said device.

20. In a tipper for cigarette machines, the combination with mechanism for continuously advancing a web of wrapping material, mechanism for continuously advancing a web of tipping material, members arranged and spaced to receive tip material and guide the same to said wrapping material, a cutter, and means imparting operating movement to said cutter across said tip material to sever a tip therefrom and against the rear cut edge of the severed tip portion in a direction lengthwise of said tipping material to push the severed tip from severing position to a position in engagement with said wrapping material, said cutter being the only means for advancing said severed tip portion.

21. In a tipper for cigarette machines, the combination with mechanism for advancing a web of wrapping material, mechanism for advancing a web of tipping material, members arranged and spaced to receive tip material and guide the same to said wrapping material, a cutter, and means imparting operating movement to said cutter across said tip material to sever a tip therefrom and against the rear cut edge of the severed tip portion in a direction lengthwise of said tipping material to push the severed tip from severing position to a position in engagement with said wrapping material, said movement imparting

means including driving parts advancing said cutter substantially at the speed of advance of said wrapping material to deliver the cut tip to said last mentioned position at substantially the same speed as that of the wrapping material, said cutter being the only means for advancing said severed tip portion. 5

22. In a tipper for cigarette machines, the combination with mechanism for continuously advancing a web of wrapping material, of mechanism for continuously advancing a web of tipping material at a slower speed than that of the wrapping material, a cutter for cutting tips from said tip material, means providing a tip-way from tip cutting position to a position in engagement with the wrapping material, and operating means for said cutter imparting feeding movement thereto at substantially the speed of the wrapping material to advance the severed tips along said way. 10

23. In a tipper, the combination with mechanism for continuously advancing a web of paper, of mechanism for continuously advancing a web of tipping material at linear speed less than that of the paper, a device for applying paste at regular intervals to the traveling paper web, a rotary cutter moving at a constant linear speed equal to that of the paper for cutting the web of tipping material and operating to advance the cut strips into register with successive pasted sections of the paper, and means for pressing said registered 25 portions into adhering relation with the pasted sections of the paper. 30

24. In a tipper, the combination with mechanism for continuously advancing a web of paper, of mechanism for continuously advancing a web of tipping material at a linear speed less than that of the paper, a device for applying paste at regular intervals to the traveling paper web, and a member rotating constantly at the linear speed of the paper and operating to sever lengths 40 from the web of tipping material and advance them into register with successive pasted sections of the paper web. 45

25. In a tipper, the combination with mechanism for continuously advancing a web of paper, of mechanism for continuously advancing a web of tipping material at a linear speed less than that of the paper, a device for applying paste at regular intervals to the traveling paper web, and a member rotating constantly at the linear speed of the paper and operating to sever lengths 50 from the web of tipping material and advance them into register with successive pasted sections of the paper web, and press them into adhering relation therewith. 55

26. In a tipper, the combination with means for advancing a web of paper, of means for advancing a web of tipping material, a device for applying paste at regular intervals to the traveling paper web, mechanism for severing lengths 60 from the web of tipping material and advancing them into register with successive pasted sections of the paper web, and means acting to detect absence of severed lengths of tipping material in said mechanism while the same is operating to 65 advance a severed length, and thereupon incapacitate the means for advancing the web of tipping material. 65

27. In a tipper, the combination with means for advancing a web of paper, of means for advancing a web of tipping material, a device for applying paste at regular intervals to the traveling paper web, mechanism for severing lengths 70 from the web of tipping material and advancing them into register with successive pasted sections 75

- of the paper web, means acting to detect absence of severed lengths of tipping material in said mechanism while the same is operating to advance a severed length, and thereupon incapacitate the means for advancing the web of tipping material and the means for advancing the paper web.

28. In a tipper, the combination with means for advancing a web of paper, of means for advancing a web of tipping material, a device for applying paste at regular intervals to the traveling paper web, mechanism for severing lengths from the web of tipping material and advancing them into register with successive pasted sections of the paper web, and means acting to detect absence of severed lengths of tipping material in said mechanism while the same is operating to advance a severed length, and thereupon in-
